CLAIM

I claim the ornamental design for a combination cigarette and cigarette lighter holder, as shown and described.

DESCRIPTION

FIG. 1 is a perspective view of a combination cigarette and cigarette lighter holder;

FIG. 2 is a left side elevation view thereof;

FIG. 3 is a front elevation view thereof;

FIG. 4 is a right side elevation view thereof;

FIG. 5 is a back elevation view thereof;

FIG. 6 is a top plan view thereof; and,

FIG. 7 is a bottom plan view thereof.

The claimed unit may be used for storing and caring purposes. The vertical shading lines are for illustrative purpose only and form no part of the claimed design.
